VEHICLE SIGNAL LIGHT

Joseph Nagy, 1513 Sherwood Court,
Dearborn, Mich. 48124

Filed Mar. 2, 1970, Ser. No. 21,701

Term of patent 14 years

Int. Cl. D12—99

U.S. Cl. D48—32

FIG. 1

5

FIG.2 5

FIG.3

FIG.4

FIG.5

FIG. 6

FIG. 1 is a side elevation view of a vehicle signal light embodying my new design.

FIG. 2 is an enlarged top plan view thereof.

FIG. 3 is an enlarged front elevation view thereof.

FIG. 4 is an enlarged side elevation view thereof.

FIG. 5 is a greatly enlarged sectional view taken on line 5—5 in FIG. 2.

FIG. 6 is an enlarged rear elevation view thereof.

The broken line showing of the vehicle in FIG. 1 is for illustrative purposes only.

I claim:

The ornamental design for a vehicle signal light, as shown and described.
